UNITED STATES PATENT OFFICE.

EVERETT CRESSE, OF OMAHA, NEBRASKA.

WINDOW-FRAME.

1,384,516.

Specification of Letters Patent. Patented July 12, 1921.

Application filed June 29, 1920. Serial No. 392,801.

To all whom it may concern:

Be it known that I, EVERETT CRESSE, a citizen of the United States of America, residing at Omaha, in the county of Douglas 5 and State of Nebraska, have invented certain new and useful Improvements in Window-Frames, of which the following is a specification, reference being had therein to the accompanying drawing.

- 10 The invention relates to window frames and has for its object to provide a device of this character so constructed, that the sashes, both lower and upper may be easily and quickly removed from the frame.
- 15 A further object is to provide a window frame so constructed that the inside stops may be removed, thereby allowing the removal of the lower sash, after which portions of the frame jamb may be pivoted inwardly so that the parting strips carried by the pivoted portions of the jamb may be moved inwardly to a position where they will allow the removal of the upper sash.
- 20 A further object is to provide a window frame having vertically pivoted jamb portions which carry parting strips and so pivoted that they may be moved inwardly for allowing removal of the upper sash. Also to provide inside stops having L-shaped hooks 25 adapted to engage apertures in the pivoted portions of the jambs for holding said pivoted portions in position, said L-shaped hooks being moved out of engagement with the pivoted portions of the jambs by forcing the inside stops upwardly. Also to provide a spring actuated member carried by each of the stops for engaging an aperture in the window frame for holding the stops in locked position.
- 30 With the above and other objects in view the invention resides in the combination and arrangement of parts as hereinafter set forth, shown in the drawings, described and claimed, it being understood that changes in 35 the precise embodiment of the invention may be made within the scope of what is claimed without departing from the spirit of the invention.

In the drawings:

- 40 Figure 1 is a perspective view of the window frame.
- 45 Fig. 2 is a vertical sectional view taken on line 2—2 of Fig. 1.
- 50 Fig. 3 is a horizontal sectional view through the window frame.
- 55 Fig. 4 is a vertical sectional view through

one of the inside stops and one of the pivoted jamb portions.

Fig. 5 is a perspective view of one of the inside stops.

Fig. 6 is a perspective view of one of the spring actuated inside stop holding members.

Fig. 7 is a detail perspective view of the frame and sill showing the hinge for the lower portion of the hinged stop.

Fig. 8 is a detail perspective view showing the upper hinge of one of the pivoted stops.

Fig. 9 is a detail sectional view showing the method of attaching the sash cord to one of the sashes.

Referring to the drawings, the numeral 1 designates the window frame and 2 the weight boxes thereof. The window frame 75 1 is of a conventional construction with the exception that the portions 3 of the window jamb 4 are hingedly connected to the facing 5 at their upper and lower ends so that said portions 3 may be pivoted inwardly. 80 The hinge pintles 6 are carried by hinges 7 and 8. The hinges 7 are at the upper ends 85 of the pivoted jamb sections 3 and their leaves 8^a are secured to the top of the window frame by means of screws 9. The 90 leaves 10 of the hinges 7 are secured to the upper ends of the jamb sections 3 by means of screws 11, said portions 3 being secured adjacent the ends of the hinge leaves 10 so that when jamb portions 3 are pivoted 95 outwardly, they will be disposed adjacent the inside faces 12 of the window frame and when pivoted inwardly they will engage the faces 13 within the weight boxes 2 as shown in Fig. 3. The lower pintles 6 are carried 100 by the hinges 8, which hinges have their leaves 14 secured to the window sill by means of screws 15 and their leaves 16 secured to the bottom end of the pivoted jamb sections 3 by means of screws 17. The lower portions of the pivoted jamb sections 3 are secured to the leaves 16 adjacent their ends so that when the pivoted jamb sections are pivoted outwardly, they will be disposed 105 adjacent the inside faces 12 of the window frame, and when in normal position as shown in Fig. 3, they will engage the surfaces 13 within the weight boxes. The parting strips 19 are carried by the pivoted jamb sections 3 and between the parting 110 strips 19 and the inside stops 20, the lower sash 21 is adapted to move when said sash is

being raised or lowered. Upper sash 22 slides upwardly and downwardly between the parting strips 19 and the outside stops 23.

The inside stops 20 are provided on their inner faces with plate carried hooks 24, which hooks are adapted to be received by apertures 25 in plates 26, which plates are carried by the pivoted jamb sections 3. By providing hooks it will be seen that the inside stops 20 may be removed by simply forcing the stops upwardly until the hooks 24 are moved out of engagement with the apertures 25, after which the lower sash 21 may be removed, and the sash cord pins 27 pulled out of engagement with the apertures 28 in the sash 21. Stops 20 having been moved it will be seen that the parting strips 19 may be moved out of engagement with the upper sash 22 by pivoting outwardly the pivoted jamb sections 3, after which the upper sash 22 may be easily removed. When it is desired to replace the sashes, the operation is reversed.

Inside stops 20 are normally held against displacement by means of plate carried pins 29, said pins being slidable in plates and normally held in engagement with the apertures 30 in the pivoted jamb sections 3 by means of springs 31. It will be seen that when it is desired to remove the inside stops, it will only be necessary to grasp the knobs 32, pull the pins 29 out of engagement with the apertures 30 against the action of the springs 31, which have been bowed by the outward movement of the pins, then raise upwardly so that the hooks 24 may be removed through the apertures 25 in plates 26.

From the above it will be seen that a window frame is provided wherein the lower and upper sash may be easily and quickly removed and one wherein the sashes may be easily and quickly replaced.

If so desired fillets 33 may be placed in the bottoms of the weight boxes 2 for limiting the inward movement of the pivoted jamb sections 3. However, the inside stops are preferably made wide enough so that they will engage the surfaces 34 so that the stops will prevent the inward pivotal action of the pivoted jamb sections 3.

The invention having been set forth what is claimed as new and useful is:—

The combination with a window frame having upper and lower sashes slidably mounted therein between outer stops, inner stops and parting strips, said parting strips being carried by pivoted jamb sections, said jamb sections being pivoted adjacent the inner facing of the frame, the inner stops being provided with L-shaped lugs adapted to engage plates carried by the pivoted jamb sections, said inside stops terminating spaced from the top of the frame thereby allowing the L-shaped lugs to be moved out of engagement with the plates of the pivoted jamb sections, and spring actuated pins carried by the inside stops and adapted to engage apertures in the pivoted jamb sections for holding the L-shaped lugs in engagement with the plates of the pivoted jamb sections.

In testimony whereof I hereunto affix my signature.

EVERETT CRESSE.
